CLAIM

The ornamental design for a connector for a recreational structure, shown and described.

DESCRIPTION

FIG. 1 is a perspective view of a connector for a recreational structure according to the subject matter disclosed herein;

FIG. 2 is a front view of a connector for a recreational structure according to the subject matter disclosed herein;

FIG. 3 is a bottom view of a connector for a recreational structure according to the subject matter disclosed herein;

FIG. 4 is a top view of a connector for a recreational structure according to the subject matter disclosed herein;

FIG. 5 is a side view of a connector for a recreational structure according to the subject matter disclosed herein; and,

FIG. 6 is a back view of a connector for a recreational structure according to the subject matter disclosed herein.

The broken line showing of the connector is included for the purpose of illustrating portions of the article and forms no part of the claimed design.
